UNITED STATES PATENT OFFICE.

SYLVESTER W. KIRK, OF CINCINNATI, OHIO, ASSIGNOR TO THE KIRK & BLUM MANUFACTURING COMPANY, OF CINCINNATI, OHIO, A CORPORATION OF OHIO.

HEAT-INSULATING STRUCTURAL ELEMENT.

Application filed June 13, 1927. Serial No. 198,372.

This invention relates to heat insulating structural panels for use in building commercial ovens as well as for constructing refrigerating or cooling chambers.

5 An object of this invention is to provide panels of the class referred to which permit of the use of sheet metal for the side walls and at the same time avoid completely the possibility of the passage of heat between 10 said side walls.

Another object is to provide a simple and strong edge structure for said panels so as to completely inclose a mass of suitable heat insulating material within the panel and at 15 the same time provide a simple and strong joint member whereby similar panels may be connected at their edges.

Another object is to provide panels which may be utilized to provide a complete oven 20 or refrigerating chamber if desired, the same type of panel being usable for wall and roof structure.

These and other objects are attained by the means described herein and disclosed in 25 the accompanying drawings in which:

Fig. 1 is a fragmental perspective view of the panel of the invention.

Figs. 2, 3 and 4 represent cross sectional views taken on any one of the edges of a 30 panel such as shown in Fig. 1, as for example on line A—A, the several views indicating modifications of structure for the edges of the panels.

Fig. 5 is a fragmental cross sectional view 35 of the type indicated in Fig. 2, showing a pair of panels joined together as in a typical wall structure.

Fig. 6 is a fragmental cross sectional view 40 of a preferred form of panel structure and the preferred form of joint such as may be had with this as well as the other panels herein shown.

Fig. 7 is a cross sectional view showing a 45 corner structure which may be made with the panels of the invention.

Fig. 8 is a cross sectional view indicating a possible floor and side wall corner construction.

Fig. 9 is a cross sectional view showing a 50 modified form of edge and joint structure for panels of the invention.

Fig. 10 is a fragmental perspective view showing a complete structure built of the panels of the invention.

55 In providing material whereby commer-

cial ovens and refrigerating chambers may be conveniently and rapidly built it is essential that in order to avoid extended and expensive work on the job, such materials should be arranged and prepared in the form 60 of panels. In the present invention the panel 12 is conveniently formed with sheet metal sides 13 and 14 and reinforced corners comprising steel angle strips such as 15 (see Figs. 2, 3, 4, 5 and 9) about which the edges 65 of the sides 13 and 14 are turned and clamped to provide tongues 17. The side walls are secured in spaced relation so as to form a hollow inclosing structure by means of strips 18 of hard heat insulating material 70 which may be prepared of cement and asbestos fiber or any other suitable composition or material. The angle strips 15 along a given side of the panel have the flanges 150 aligned so that the strip of hard insulation 18 may 75 be secured to the flanges 150 by any suitable means such as rivets 19 or screws or bolts or any other convenient fastening means may be used. The strip 18 of hard insulation is of a thickness such as to provide a strength substantially equal to that of the steel angle pieces 15 to which it is secured. The panels 80 may readily be manufactured in shapes of angular, U-shaped or curved cross section, such modifications being readily provided by 85 using different forms of insulating frames about which the metallic wall members may be attached.

The edge structure of the panel being uniform along the four sides, it will be noted 90 that a closed chamber 20 is had within the panel. This chamber 20 is adapted to be filled with insulation material such as asbestos fiber or any other suitable material, the choice of which will be governed largely by 95 the purpose for which the panels are to be used. This construction is efficient for high temperature ovens.

From the foregoing it will be noted that 100 there is no metallic or heat conducting structure connecting the opposite sides 13 and 14 of the panels. At the same time the panel structure is made strong and is arranged to provide for the interlocking of adjacent panels to form a substantially continuous 105 wall without the aid of additional connection means. This arrangement eliminates the disadvantages attending the structures wherein soft sheet insulation is disposed between abutting or slidable joint members and 110

instead provides a strong and positive metal to metal bearing between connected panels.

As shown in Fig. 2 the insulating strip 18 terminates at a distance from the angles 5 15 providing a groove 21 in which the tongue 17 of an adjacent panel may seat. In Fig. 5 is shown a pair of panels such as shown in Fig. 2 united in one form of typical wall structure. In connecting the panels it will 10 be noted that the tongue 17 of one side of a given panel enters the groove 21 on the same side of the next panel. On the opposite side of said panels the relative positions of the tongue and groove are reversed so that ad- 15 joining panels are staggered by the thickness of tongue 17. The tongues 17 project for such length as to preclude abutment of the opposed faces of strips 18 when a pair of panels are joined. The space between the 20 strips 18 may be filled with suitable soft packing 16 in order to provide a more nearly perfect insulation between the sides 13 and 14 of the joined panels.

Fig. 6 shows a preferred form of edge 25 structure for panels of the invention. In Fig. 6 is shown a preferred form of lateral connection between panels. The edge structure of the panel includes a specially formed strip having the flange portions 15 and 150 30 and an intermediate channel portion 1500 which in this embodiment provides the groove 21. The joint as shown in this view has both tongues 17 of a given panel inserted in the grooves 21 of an adjoining panel 35 thereby producing a wedged joint. It will be readily understood that the other forms of panel may be likewise joined.

The modified form as shown in Fig. 3 40 differs from the structure shown in Fig. 2 in that the hard insulation side strip 18 abuts the angle strip 15 on one side so that there is provided but a single groove 21. In each of these forms as shown in Figs. 2 and 3 the strips 18 are secured exteriorly of the angle 45 flanges 150. In Figs. 4 and 6 are disclosed modifications wherein the insulating strip 18 is secured to the innermost faces of the flanges 150, the modification as shown in Fig. 4 having no recess for receiving the 50 tongue 17 while the form shown in Fig. 6 uses a special flanged channel strip in lieu of the simple angle strip 15.

The manner of joining panels of the several modified forms will be readily evident 55 in view of the detailed explanation of Figs. 5 and 6.

In Figs. 7 and 8 respectively are shown 60 a simple and strong means for securing panels in the horizontal as for floor and ceiling, with side wall panels. This corner section as shown in Fig. 7 comprises an angle iron 26 connecting adjacent tongues 17 of the panels to be joined. Suitable bolts 28 as shown may be used for this purpose or rivets 65 or screws may be used if desired. In order

to effect a tighter corner joint, a sheet iron angle 29 may be included. A sheet metal cornice strip 30 is used to bridge over the open ends of the panels so as to provide a hollow chamber 31 which may be filled with 70 loose insulation. The cornice may be of relatively thin metal, turned upon itself as at 32 and having an end portion 33 which will conveniently hook on to the tongues 17. Suitable screws 34 may be passed through 75 the cornice into tongues 17 to preclude displacement thereof.

As shown in Fig. 8 the panels 12 may in some cases be used as a base or floor wall 80 of a chamber, in which case they would be attached to the said walls in substantially the manner just described, suitable angle irons 35 being disposed exteriorly of the vertical walls in order to strengthen and to avoid displacement thereof. If desired, the 85 bottom edges of the panels 12, arranged in a side wall as shown in Fig. 10, may be inserted between a pair of angle irons secured to a floor. In such installation any suitable 90 insulation may be used to fill the space between tongues 17 and if desired, relatively thin strips of the hard insulation may be used to insulate the sheets 13 and 14 from the angle irons. It will be understood that 95 in some cases a heavy duty floor may be required for the chamber and that in such cases the floor may be suitably insulated from the outer wall portions of the chamber. In Fig. 10 there is indicated a possible 100 chamber or oven construction wherein the side walls and roof are joined by means of the typical corner structure shown in Fig. 7, the completed structure being finished exteriorly with plaster in the manner shown in Fig. 5.

The side of the panel which is to be disposed on the outside of a structure may be desired to be plastered or otherwise finished. It will be understood that one of the sides for example 14 of the panels may be made of 110 ribbed or expanded metal as indicated in Fig. 5 or it may be of any other suitably prepared sheet metal in order to form a suitable base upon which plaster 22 may be bonded.

In those panels having an exterior plaster finish, it is found desirable to provide a longitudinal division as at 23 in the plaster 120 22 so as to permit separation of the panels without breakage of the exterior finish. This is found to be highly desirable in the event of alterations or moving of an oven or another chamber formed of the panels. In a joint of this kind a pair of canvas or other suitable flexible flaps 24 and 25 may 125 be embedded one in each of adjacent panels so as to be overlapped to provide a neat flat joint.

Inasmuch as the panels are adaptable for 130 all types of fixed and movable structures the

various installations which are possible are not shown. The simple structure indicated in Fig. 10 will be sufficient for the purpose of illustrating one of the numerous possible

5 installations.

In the manufacture of panels of the invention four strips of the hard insulation material 18 would be placed at right angles to one another with the angle members 15 10 secured thereto thus forming a rectangular frame. The relatively thin sheet metal wall 13 would then be secured to one side of the frame, the edges being turned about and clamped upon the projecting portions of the 15 angle members 15 thereby forming the tongues 17 on one side. The frame would then be filled with a comparatively light weight insulating material 36, the nature of the material being determined to some 20 extent by the use to which the panels are to be put. The side 14, which may be plain sheet metal or ribbed metal or metal lath is then secured over the remaining side of the frame, thereby completely inclosing the 25 insulating material. If desired the turned over edges of the sides 13 and 14 may be additionally secured to the angle members by spot welding or any other suitable means.

The tongue and groove interlocking feature of the panels greatly facilitates the erection of a wall, said panels being adapted for interlocking engagement with other panels on any of the four edges. The absence of metal connecting the inner and 35 outer sheet metal sides provides a very efficient resistance to the passage of heat through the panels and this efficiency is attained without the sacrificing strength and without requiring unsightly or expensive 40 auxiliary securing means.

The interlocking joint between adjacent panels illustrated typically in Figs. 5 and

6, is strong and substantial, and yet renders dismantling of a wall and removal of the 45 panels very rapid and easy.

What is claimed is:

1. In a heat insulated chamber structure the combination of panels comprising hollow frames of heat insulating material, metallic side walls secured on opposite edges 50 of the frames and heat insulated from one another thereby, overhanging edges on said side walls providing spaced tongues on the panels, an angle member secured to one pair of tongues on angularly disposed panels for 55 providing an interior corner connection, a cornice member connecting the remaining tongues on said panels for providing an exterior corner connection in heat insulated relation to the first mentioned corner connection, suitable insulating material contained between the corner connections and disposed interiorly of the panels, the interior wall of the completed chamber structure being entirely free of metallic connection 60 with the exterior wall of said structure.

2. A heat insulating structural panel of the class described comprising a substantially rectangular frame formed of transversely disposed strips of hard heat insulating material, metallic angle members secured adjacent the edges of said strips, sheet metal side walls secured to the angle strips and heat insulating material contained in and filling the space between the sheet metal, 70 the opposed sheet metal side walls and their respective securing means being secured in spaced apart relation entirely by non-metallic material.

In testimony whereof, I have hereunto 80 subscribed my name this 8th day of June, 1927.

SYLVESTER W. KIRK.
